UNITED STATES PATENT OFFICE.

THOMAS W. TALIAFERRO, OF OMAHA, NEBRASKA, ASSIGNOR TO THE CUDAHY PACKING CO., OF CHICAGO, ILLINOIS, A CORPORATION OF ILLINOIS.

CLOSURE FOR BOTTLES, JARS, OR OTHER VESSELS.

SPECIFICATION forming part of Letters Patent No. 747,269, dated December 15, 1903.

Application filed July 28, 1903. Serial No. 167,333. (No model.)

To all whom it may concern:

Be it known that I, THOMAS W. TALIAFERRO, a citizen of the United States, residing at Omaha, in the county of Douglas and 5 State of Nebraska, have invented new and useful Improvements in Closures for Bottles, Jars, or other Vessels, of which the following is a specification.

My invention relates to improvements in 10 closures for bottles, jars, or other vessels, and has for its object to provide such a closure having a novel, simple, and inexpensive withdrawing device.

To the end stated, my invention consists in 15 a vessel-closure, such as a cork, and withdrawing device therefor, the body of which device is attached or secured to the outer or exposed face of the closure and has an extension that is wrapped over one end of the 20 closure across the inner or concealed face thereof and then over the opposite side or edge of the closure, and the free end of which is left exposed in position to be grasped and drawn upon to withdraw the closure from the 25 vessel.

The invention is illustrated in the accompanying drawings, in which—

Figure 1 is a perspective view of a closure provided with my improved withdrawing device. Fig. 2 is a view showing such closure and applied withdrawing device about to be inserted into the mouth of a jar. Fig. 3 is a view illustrating said closure and applied withdrawing device inserted into and closing 35 the mouth of a jar. Fig. 4 is a view illustrating the action of withdrawing the closure from the mouth of a jar.

In the said drawings the reference-numeral 1 designates a vessel-closure, preferably a 40 cork, of approximately disk-like formation and suitably fashioned to close the mouth of the vessel into which it is to be introduced.

The numeral 2 designates the body of the closure-withdrawing device, which prefer- 45 ably and as shown corresponds in shape to that of the outline of the closure. It is attached to the outer or exposed face of the closure in any suitable way, as by glue or cement, (with which it may be previously 50 supplied or with which it may be provided

at the time of attachment to the closure,) and is provided with an extension, preferably and as shown, in the form of a relatively thin and elongated strip 3, the length of which must be in excess of the diameter of the closure 55 and the height of the two sides thereof. This extension-strip is wrapped over one side or edge of the closure, as illustrated at 4, is then extended across the inner or concealed face of the closure, as shown at 5, thence over the 60 opposite side or edge of the closure, as at 6, and the extremity thereof is left free to serve as a pulling end 7 by drawing or pulling on which the closure is withdrawn.

It will be seen that in the act of withdraw- 65 ing a closure from a jar or other vessel the free pulling end 7 is drawn upon, lifting the adjacent edge of the closure, as illustrated in Fig. 4, and by the continued pulling the closure is entirely withdrawn.

The body portion 2 of the withdrawing de- 70 vice, attached to the exposed or outer surface of the closure, may be utilized as a label or for the purpose of printing advertising mat- 75 ter thereon, and it will be apparent that the entire withdrawing device may consist of a label of any suitable kind having an exten- 80 sion 3 wrapped or folded about the side walls and edges of the closure and across its inner or concealed face, as described.

According to my invention an effective clo- 85 sure-withdrawing device is provided, which in addition may serve as a suitable label or advertising medium. No modification or change of construction of usual manner of closure device is necessary according to my invention, as my improved closure-withdraw- 90 ing device may be applied to existing con- structions of closures by mere attachment or application thereto without in any wise re- 95 quiring any new construction of closure or modification or change of existing construc- tions thereof.

The closure-withdrawing device may be made of paper of sufficient stoutness or of 95 paper lined with a strengthening fabric or of a fabric, as may be desired, or an additional layer of paper may be used for strength- ening purposes.

By reason of the manner of the application 100

of the closure-withdrawing device to a closure, as herein described, it is obvious that the force applied in the act of withdrawal does not tend to separate the withdrawing device from the closure, as would be the case if the extension were not wrapped over the edges and across the inner face of the closure, as set forth.

Having thus described my invention, what I claim is—

A closure for vessels provided with a withdrawing device the body of which is secured to the outer or exposed face of said closure

and is provided with an extension wrapped about the side walls of the closure and across the inner or concealed face thereof and having an exposed, free extremity to serve as a pulling end, substantially as described.

In testimony whereof I have hereunto set my hand in presence of two subscribing witnesses.

THOMAS W. TALIAFERRO.
